UNITED STATES PATENT OFFICE

2,163,197

CHIMNEY COWL

Patrick J. Fitzgerald, Prescott, Ariz.

Application March 29, 1938, Serial No. 198,770

1 Claim. (Cl. 98—68)

My invention relates to improvements in chimney cowls or hoods and the primary purpose of the invention is to provide a simply constructed, inexpensive device of this character adapted to be readily attached to the usual chimney and particularly designed to prevent down-draft while at the same time facilitating up-draft.

Another object is to provide a device of the character and for the purpose above set forth embodying an improved anti-friction mounting for the cowl proper whereby the latter may be easily turned by the wind and without creaking or screeching noises such as usually occur in the chimney cowls as commonly constructed.

15 To the accomplishment of the above, and subordinate objects presently appearing, a preferred embodiment of my invention has been illustrated in the accompanying drawings, set forth in detail in the succeeding description, and 20 defined in the claim appended hereto.

In said drawings:—

Figure 1 is a view in vertical central section of a chimney cowl constructed in accordance with my invention, and

25 Figure 2 is a similar fragmentary view with the cowl removed.

Referring to the drawings by numerals, the cowl of my invention comprises a flue member 1, preferably cylindrical, adapted to be mounted, 30 in any suitable manner, in or on the top of the chimney, not shown, to project well above the same, and a hood 2 surmounting the flue member 1 and comprising a depending skirt 3, also preferably cylindrical, larger than the flue member 35 1 and rotatably mounted, in a manner presently described, on said member in centered overlapping relation thereto to provide a by-pass opening 3' between the lower end of said skirt 3 and the upper end of said flue member 1. The hood 2 has an upper side opening 4 therein well 40 above the top of the flue member 1 and an up-standing vane 5 on the top thereof arranged so that under the action of wind the hood is turned to point the opening 4 away from the wind.

45 The mounting for the hood 2 comprises, as its basic element, an arched support 6 of channel iron having its free end riveted, as at 7, to an annulus 8 which fits over the upper end of the flue member 1 and is suitably secured thereto so 50 that the support 6 spans said member 1 in up-standing position and centrally thereof. The support 6 has suitably secured to the sides thereof, as at 9, a horizontally extending bar 6' located above the upper end of the flue member 1.

55 Extending through suitable apertures 10 and

10' provided in the upper part of the support 6 and the bar 6' centrally thereof is a vertically disposed sleeve 11 secured in position by means of a pair of upper and lower jamb nuts 12 and 13 threaded onto the sleeve and bearing against the underside of the support 6 and the top side of the bar 6', respectively. A pair of upper and lower gland nuts 14 and 15 are threaded onto the opposite ends of the sleeve 11 above the support 6 and below the bar 6', respectively, said nuts 14 and 15 also preferably bearing against the support 6 and bar 6' to function as additional securing means for the sleeve 11. The lower gland nut 15 has formed therein axially of the sleeve 11 a concave socket 16 seating a ball bearing 17 which supports an arbor 18 having a concave socket 19 in its lower end for centering said arbor on said ball bearing. The arbor 18 extends well above the sleeve 11 and upper gland nut 14, for a purpose presently seen, and is smaller in diameter than the inner bore of said sleeve to eliminate friction between said arbor and sleeve. At the upper end of the sleeve 11, a gland nut 14 is threaded thereon between which and said end of the sleeve are interposed side thrust bearings 20 25 30

The hood 2 is supported on the upper end of the arbor 18 by means of an internal upwardly arched brace, or hanger, 21 of channel iron having its ends secured, as at 22, to the inner wall of the skirt 3 and a central aperture 23 through which the arbor 18 extends, said brace, or hanger, 21 being clamped to the arbor 18 by means of a pair of nuts 24 and 25 threaded onto said arbor upon opposite sides of the brace respectively. 35

As will now be seen, the hood 2 is supported by a single ball bearing 17 and centered by the ball bearings 20 so that frictional resistance to rotation thereof is practically eliminated and said hood, under the action of wind, will be quickly and noiselessly rotated to point the opening 4 away from the wind. 40

In the operation of the invention, up-draft is created by the wind blowing past the opening 4 by way of the by-pass opening 3' over the top of the member 1 whereby the chimney is caused to draw in the usual manner. Any blast of air entering the hood 2 by way of the opening 4 may pass in greater part out of said hood by way of said by-pass opening 3' and thereby obviate dampening the chimney by down-draft in the flue member 1. 45 50 55

My invention, both as regards its structure, operation and advantages will be readily under- 55

stood from the foregoing without further explanation.

Manifestly the invention, as described, is susceptible of modification without departing from the inventive concept and right is herein reserved to such modifications as fall within the scope of the subjoined claim.

What I claim is:—

In a chimney cowl, a flue member adapted to be mounted on the top of the chimney to extend above the same, a hood surmounting the flue member and having a skirt depending therefrom over the upper end of the flue member in spaced relation thereto and a side opening therein at the top thereof and above said member, and

15

means to mount said hood on said flue member for rotation thereon comprising an upwardly arched support spanning the top of the flue member and secured thereto, a similarly shaped hanger secured to the opposite sides of the hood 5 interiorly thereof and surmounting the support, a sleeve fixed on said support in upstanding position, an arbor depending from the hanger into said sleeve, an anti-friction ball at the lower end of said sleeve supporting the lower end of the 10 arbor, and anti-friction side thrust bearings interposed between the upper end of the sleeve and said arbor.

PATRICK J. FITZGERALD.
